UNITED STATES PATENT OFFICE

119,719

DESIGN FOR A DRESS

Elizabeth Cutler, New York, N. Y.

Application February 21, 1940, Serial No. 90,387

Term of patent 3½ years

To all whom it may concern:

Be it known that I, Elizabeth Cutler, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the back view of my dress on a reduced scale.

I claim:

The ornamental design for a dress, substantially as shown.

ELIZABETH CUTLER.
